PENCIL

Jack Tamis, New York, N. Y.

Application December 18, 1936, Serial No. 116,467

3 Claims. (Cl. 120—18)

The present invention relates to propelling pencils and more particularly to propelling pencils comprising a main or body portion and a cap portion in which the marking element or lead, as it is generally called, is projected and retracted by a relative turning movement of the body and cap portions, such pencils being generally well known.

In the present invention I propose to provide such a pencil with an outer ornamental case, both the body portion and the cap portion having common ornamentation or design of such a nature that the parts thereof carried by the cap and body portions when thrown out of register with each other by the turning of the cap to operate the propelling mechanism can with certainty be recoupled so as to restore the register of the parts of the design carried by the two parts of the pencil.

A further object is to provide a locking means which will with certainty retain the cap and body portions in such position as to maintain the parts of the design in register with each other and prevent the accidental turning of the cap portion with relation to the body portion.

Further objects of the invention will appear from the following specification.

The invention is shown in the accompanying drawing in which—

Fig. 1 shows the pencil in front elevation somewhat enlarged;

Fig. 2 shows a side elevation of the pencil shown in Fig. 1;

Fig. 3 shows a very much enlarged vertical sectional view taken on a diametrical line cutting the axis, the cap portion being in elevation and extended to a position which will permit it to be turned about the vertical axis to operate the pencil mechanism;

Fig. 4 is a similar view showing the cap and other parts in elevation with the upper part of the body portion in section, the lower part being removed;

Fig. 5 is a horizontal section taken on the line 5—5 in Fig. 3 looking in the direction of the arrows on that line.

Similar reference characters will be employed to designate corresponding parts.

As shown in the drawing the pencil comprises a main or body portion 1 and a cap portion 2. The outer casing of the body portion 1 and cap portion 2 are, as before stated, of ornamental shape and appearance. In the present instance they are rectangular in cross section as indicated in Fig. 5, having oppositely disposed walls 3 and

4 arranged parallel to each other, the walls 3 being of somewhat less width than the walls 4 so that in cross section they form substantially an oblong.

In addition to being of the ornamental shape as specified, the surface may be ornamented as by the engine turning indicated at 5 preferably divided up into panels bounded by the marginal borders 6. The main or body portion 1 at its lower end will be provided with the flattened and tapered ferrule-like portion 7 through which the lead or marking material 8 may be projected and retracted at will by any usual form of propelling and retracting mechanism as shown in vertical cross section in Fig. 3. Preferably the body member 1 and the cap member 2 will be of the same size in cross section so that when placed in the condition shown in Figs. 1 and 2, with the members in close contact, they will define two rectangular members of different length, one accurately abutting and continuing the marginal boundaries of the other.

It is desirable that the parts shall remain in the position shown in Figs. 1 and 2 without any liability of accidental displacement or relative turning movement excepting when it is desired to

impart to the main and cap portions such relative turning movement to actuate the pencil mechanism to either project or retract the lead. For this purpose the cap portion 2 is connected by means of a sliding cylindrical tube 9 and an extension tube 10 to a spirally slotted sleeve 11 forming a part of the pencil operating mechanism.

The tube 10 which is connected to the tube 9 is provided with a slot 12 which engages a stud 12' carried by the slotted sleeve 11, the turning of which by means of the cap 2 and the connections just described operates the lead propelling and retracting mechanism to project and retract the lead 8 of the pencil. By means of the stud and slot connection 12 and 12', the cap tubes 9 and 10 are permitted to have a sliding movement into and out of the body portion 1

within the limits of the slot and stud connection 12 and 12' without disconnecting the cap 2 from the propelling mechanism. When the cap is withdrawn as shown in Figs. 3 and 4, it may be turned about a vertical axis corresponding to the vertical axis of the body of the pencil, and by means of the spirally slotted tube 11 cause the lead 8 to be projected beyond the tip of the ferrule-like extension 7 and retracted within the same, all in a manner common to pencils of the type shown.

All of the lead holding and propelling mecha-

- nism including the tubes 9, 10 and 11 are enclosed in a main covering tube 101 within the outer casing of the member 1 and fixedly connected at its lower end to the fixed bearing 102 in which the lower end of the tube 11 is free to turn, the bearing 102 being secured in fixed position in the lower end 1 of the casing. The tubes 9, 10 and 11 are free to turn in the tube 101 and the tubes 9 and 10 have a limited sliding movement therein to permit the cap portion to be extended when required as hereinbefore described.

The cap 2 at its lower end is provided with a rectangular flange 13 of a size and shape to accurately fit within the upper open end 14 of the ornamental outer casing of the main body portion 1, such flange being bounded by a shoulder 15 which when the cap is fitted in the open end 14 will rest against the shoulder 15 thus producing a registered fitting of the cap and main portion of the pencil as shown in Figs. 1 and 2. By "registered" fitting is meant one which insures that the ornamental shape and surface ornamentation as embodied in the cap and body portion will be brought into register with each other and when the flange 13 is inserted in the open end 14 of the body portion 1, because of the rectangular shape in cross section it will of course be locked against any accidental turning and the ornamental features embodied in the two parts will, as before stated, register with each other as indicated. At the same time, when it is desired to either propel or retract the marking lead 8, the cap 2 may be pulled out so that the flange 13 is clear of the casing as shown in Figs. 3 and 4, and thus placed in position so that it may be turned to operate the pencil mechanism and thus propel and retract the lead as required.

As shown in Figs. 1 and 2, the pencil may be provided with any usual form of clip 16, and a watch 17 may be mounted in the cap portion 2 as indicated. If a watch is embodied in the cap 2, a usual winding stud 18 will project from one side of the casing of the cap 2. The casings of the main body portion 1 and the cap 2 will preferably be made of gold, or of a base metal which may be plated if desired.

The operation of the device has been sufficiently disclosed in connection with the foregoing description of its construction and it is believed that

any further description of the operation will be found unnecessary.

I claim:

1. A propelling pencil of the screw type comprising an outer casing consisting of a main body portion and a cap portion, a propelling mechanism within the main body portion, including a spirally slotted actuator, the propelling mechanism being fixedly held but the actuator capable of a rotary movement with relation thereto, a sliding non-rotary connection between the cap portion and the spirally slotted actuator, means to limit the sliding movement of the cap portion, and means to lock the cap and main body portion against relative turning movement when the cap portion is in its retracted position and in engagement with the upper end of the main body portion.

2. A propelling pencil of the screw type comprising an outer casing consisting of a cap portion and a main body portion, the main body portion containing the propelling mechanism fixedly held therein, said propelling mechanism comprising a spirally slotted actuator, a telescopic non-rotary sliding connection between the cap portion and the actuator permitting the cap portion to be extended with relation to the main body portion and to be turned axially to operate the actuator, said cap portion carrying at its base means to lock the cap portion and body portion to prevent relative turning movement when the cap portion is retracted.

3. A propelling pencil of the screw type comprising a main body portion and a cap portion slidably connected so that they may be moved axially toward and from each other, propelling mechanism fixedly mounted in the main body portion including an actuator capable of rotating with relation to the other elements of the propelling mechanism, a telescopic sliding non-rotary connection between the cap portion and the actuator, said cap portion having at its lower end a depending flange arranged to fit the upper open end of the main body portion, whereby when the cap portion is extended it may be turned to operate the propelling mechanism and when retracted held from relative axial movement with the body portion.
